(57) **CLAIM**

The ornamental design for a hair marker, as shown and described.

DESCRIPTION

FIG. 1 is a top and side perspective view of a hair marker showing my new design, with the cap on;

FIG. 2 is a side elevational view thereof;

FIG. 3 is a side elevational view thereof from the side opposite that shown in FIG. 2;

FIG. 4 is a top plan view thereof;

FIG. 5 is a bottom plan view thereof;

FIG. 6 is a side elevational view rotated 90 degrees from the position shown in FIG. 2;

FIG. 7 is a side elevational view thereof showing the side opposite that shown in FIG. 6;

FIGS. 8-14 are views similar to FIGS. 1-7, respectively, but with the cap off; and,

FIG. 15 is a view similar to FIG. 8 but showing the side opposite that shown in FIG. 8.

The material shown in broken line forms no part of the claimed design.
